SWITCHING MECHANISM

Albert E. Baak, Minneapolis, Minn., assignor to
Minneapolis-Honeywell Regulator Company,
Minneapolis, Minn., a corporation of Delaware

Application May 7, 1937, Serial No. 141,302

26 Claims. (Cl. 200—83)

This invention relates to switching mechanism and more particularly to that type of mechanism adapted to open and/or close an electrical circuit, or circuits in response to variations in the 5 value of a condition, to operate suitable mechanism to control the condition.

One object of this invention is the provision of an improved means for adjusting the differential of such a switching mechanism whereby the 10 condition value at which the switch is, illustratively, closed may be varied and the value at which the switch is, illustratively, opened may also be varied independently of the former value.

An additional object resides in the provision of 15 such a differential adjustment means having a visual indicator for each of the condition values above mentioned whereby the same may be readily determined.

A further object resides in the construction of 20 a simplified differential mechanism having a relatively small number of operating parts and one which will be reliable in operation and adapt itself to exact calibration.

A further object is the provision of such a 25 mechanism which is sturdy, durable, reliable in operation and relatively inexpensive to construct.

Other objects will in part be obvious and in part pointed out hereinafter.

The invention accordingly consists in the combinations of elements, arrangements of parts and 30 features of construction, all as will be more fully pointed out hereinafter and disclosed in the accompanying drawing wherein:

Figure 1 is a front elevational view of one form 35 of mechanism embodying the instant inventive concept.

Figure 2 is a side sectional view taken along the line 2—2 of Figure 1 as viewed from the right.

Figure 3 is a fragmentary view showing certain 40 parts of the mechanism as shown in Figure 1, certain other parts thereof being broken away for the sake of clarity.

Figure 4 is a side elevational view of the mechanism shown in Figure 1 as viewed from the left, 45 certain portions being cut away, and

Figure 5 is a perspective view showing certain details of construction.

Similiar reference characters refer to similar 50 parts throughout the several views of the drawing.

Having now particular reference to the drawing, there is generally indicated at 10, a casing to which is secured in any suitable manner a housing 11, which contains a conventional Sylphon bellows and its associated springs (not shown). The

bellows is caused to contract and expand in a known manner in accordance with changes in temperature or pressure in any space the condition value of which it is desired to control, as by means of a capillary tube and volatile fluid filled bulb (not shown) or a conventional pressure tube leading from the said space to housing 11. 5

An operating rod 12 is secured to the bellows and caused to move upwardly or downwardly thereby, as is well known in the art. Operating 10 rod 12 is provided with a pointed tip 13, as best shown in Figure 2, which engages a recess in a boss 14 which comprises a portion of a lever 15, lever 15 being freely mounted on point 13 in such manner that it may pivot or oscillate freely thereon subject to limitations by structure to be hereinafter pointed out. 15

Lever 15 is provided at its extremities with a pair of points 16 and 17 which engage suitable recesses in bosses 18 and 19 respectively. Boss 20 18 is carried by a lever 20, and boss 19 by a lever 21.

Levers 20 and 21 are fulcrumed on a member generally indicated at 25 secured as by screws 26 to the base of casing 10. As better shown in Figure 5, member 25 comprises an upwardly extending portion 27 provided at its upper extremity with a transversely extending portion 28 to which latter are secured a pair of knife edged elements 29 and 30 positioned for engagement with suitable knife edge receiving grooves in levers 20 and 21 respectively. Knife edge members 29 and 30 may be secured to transversely extending portion 28 as by screws 31 in order that the same may be readily removed for replacement in the event that such replacement is necessary or desirable. 30 35

Having particular reference to lever 20, the same is provided with an aperture through which passes a screw 40 provided with a head 41 carrying projections 42 thereon. Screw 40 threadedly engages a boss 43 to which is secured one end of a coil spring 44. The other end of coil spring 44 is secured to a second boss 45 provided with an extending projection 46. A screw 47 provided with an enlarged head 48 extends through the top wall of casing 10 and threadedly engages boss 45. Projection 46 extends outwardly through an aperture 50 in the side wall of casing 10 and terminates adjacent a scale plate 51. 45 50

Thus it will be seen that the tension of spring 44 biases lever 20 upwardly against its associated knife edge 24 and correspondingly forces boss 18 into engagement with point 16.

A stop member generally indicated at 52 is se- 55

cured to the side wall of casing 10 adjacent the distal end of lever 21 and serves as a stop to limit the movement thereof in a manner to be described hereinafter.

5 Having reference now to lever 21 it will be seen that the same is provided, as best shown in Figure 3, with an aperture through which extends a screw 55 similar to screw 40 and likewise provided with an enlarged head 56 having projections 57 thereon adapted to engage a lower surface of lever 21 adjacent the sides of the aperture therein. Screw 55 similarly engages a boss 58 to which is secured one end of a coil spring 59 identical to coil spring 44. The other end of spring 59 is likewise secured to a boss 60 provided with a projection 61. A screw 62 provided with an enlarged head 63 threadedly engages boss 60. Projection 61 similarly extends exteriorly of casing 10 through a slot 62 and terminates adjacent scale 20 plate 51.

Thus from the foregoing it will be seen that each of levers 20 and 21 is biased upwardly against their respective knife edges 29 and 30 by their respective springs 44 and 59.

25 Stop member 52, which also serves to limit movement of the distal end of lever 21, is, as better shown in Figure 4, comprised of a channel shaped member secured as at 53 by spot welding or in any other desired manner to the side wall of casing 10 and provided with slots 54 adjacent the ends of levers 20 and 21 wherein these ends may move.

Lever 20 is provided with an upwardly extending portion 70 which may be integral therewith and which terminates in a flattened portion 71. Lever 21 is similarly provided with an extending portion 72 having at its extremity an angularly disposed lug 73 which extends in the direction of portion 70. Lug 73 thus serves as a spacer and when portions 70 and 72 are moved in a manner to be hereinafter described the arrangement is such that they are at all times at least a minimum distance apart, such minimum being defined by the thickness of lug 73. Pivoted to portion 72 as by pivot pin 74 is a lever 75, the extremity of which is provided with a flattened portion 76 similar to, but oppositely disposed with respect to portion 71. An elongated slot 77 in member 75 surrounds a pin 78 fixedly associated with member 72 and a spring 80 extends between a suitable aperture in a projection 81 of member 75 and a second aperture in a projection 82 of member 72. Thus it will be seen that in the absence of external pressure thereon, members 72 and 75 move as an integral unit but upon application of such pressure in a manner to be described hereinafter, spring 80 serves as a strain release, member 75 being permitted pivotal motion about pivot 60 74 to an extent defined by the limits of slot 77.

65 Flattened surfaces 71 and 76 are positioned on opposite sides of a pin 90, which comprises an integral portion of a member 91 pivotally secured as on a pivot screw 92 to one leg 93 of a bracket generally indicated at 94. The other leg 95 of bracket 94 carries a mercury tube switch clip 96 which in turn supports a mercury tube switch 97. A pivot pin 98, secured as indicated at 99 to the rear wall of casing 70 10, passes through suitable apertures in legs 93 and 95 of bracket 94 whereby the latter is pivoted thereon. Any suitable means such as a wire clip 100 may be utilized to maintain bracket 94 in assembled relation with pin 98. A set 75 screw 101 carried by leg 93 of bracket 94 passes

through a suitable slotted aperture 102 in member 91 to permit suitable positioning of pin 90 to allow for factory calibration of the instrument in a known manner. A conventional alignment pendulum 105 is positioned within and pivoted as at 106 to the rear wall of casing 10 in order that the instrument may be properly aligned in mounting the same.

From the foregoing the operation of the device should now be readily apparent to those skilled in the art. Assuming for the purposes of illustration that the tension in springs 44 and 59 is identical, it will be seen that upward movement of operating rod 12 is transmitted through transversely extending member 15 simultaneously to levers 20 and 21 and hence to members 70, 72 and 75 and that such movement in turn being transmitted through flattened portions 71 and 76 to pin 90 will occasion a tilting movement of mercury switch 97. Thus an increase in pressure in housing 11 forcing transversely extending member 15 upwardly will rotate levers 20 and 21 simultaneously in a counter-clockwise direction as viewed in Figure 1 and through the abutment of flattened surface 76 with pin 90 25 tilt mercury switch 97 to a position opposite that in which it is shown in Figure 1, assuming, of course, that the said increase in pressure is of sufficient intensity to overcome the pull exerted by springs 44 and 59. Upon a decrease in pressure however, operating rod 12 will move downwardly to permit the tension of springs 44 and 59 to rotate levers 20 and 21 respectively in a clockwise direction, as viewed in Figure 1, to return the switch to the position 30 in which it is shown in the drawing.

Assume now however that it is desired that the mercury switch assume one position upon the achievement of one temperature or pressure value and return to its opposite position upon the 40 achievement of a second and different value.

For the purposes of illustration, assume that it is desired that mercury switch 97 tilt from the position shown in Figure 1 to its opposite position upon the achievement of a pressure in 45 housing 11 of, say, 5 lbs. and return to the position shown only upon the achievement of a pressure of 3 lbs., thus providing a two-pound operating differential. Screws 48 and 63 are rotated, which rotation, it will be understood, varies 50 the tension in springs 44 and 59 respectively until their corresponding pointers 46 and 61 indicate the desired number of pounds on scale plate 51.

Now it will be seen that upon an increase in 55 pressure in housing 11, operating rod 12 is moved upwardly against the combined tension of the two springs 44 and 59. However, no movement of either levers 20 or 21 takes place until the pressure of housing 11 is slightly in excess of 60 3 lbs. at which time the tension of spring 44 will be overcome. Since the tension in spring 59 is still sufficiently strong to withstand the pressure exerted by operating rod 12, point 17 will remain stationary while transverse member 65 15 is tilted about point 17 as a fulcrum to move point 16 upward as viewed in Figures 1 and 2. Such upward movement will cause a counter-clockwise rotation of lever 20 about its associated knife edge 24 and a corresponding movement of member 10 and hence flattened portion 71 in a direction away from pin 90. Such movement will continue until the distal end of lever 20 abuts the lower portion of its associated slot 54 whereupon further rotation of lever 20 70 75

in a counter-clockwise direction being precluded, the parts will remain stationary until such time as the pressure in housing 11 increases to a point slightly in excess of 5 lbs. whereupon point 17 5 will move upwardly against the tension of spring 59, point 16 serving as a fulcrum for member 15, and consequently rotate lever 21 in a counter-clockwise direction until the distal end of lever 21 engages the lower extremity of its associated 10 slot 54.

Such movement of lever 21 will result in a corresponding movement of member 72 and hence member 75, whereupon flat surface 76, will through its abutment with pin 90, tilt mercury switch 97 to its opposite position. Assuming now 15 that the pressure decreases, it will be seen that as the pressure in housing 11 drops to a point slightly below 5 lbs. lever 21 will be moved about its associated knife edge 30 in a clockwise direction until limited by the upper portion of stop 52, 20 in this case point 16 again serving as a fulcrum about which member 15 rotates in a clockwise direction as viewed in Figure 2. When lever 21 has reassumed the position in which it is shown 25 in Figure 1 the parts will remain relatively motionless until the pressure has continued its descent to a point slightly below 3 lbs. whereupon, the point 17 serving as a fulcrum, lever 20 will be moved in a clockwise direction by spring 44 to 30 return member 70 to the position shown in Figure 1 whereupon flat surface 71 will, through its engagement with pin 90, return mercury switch 97 to the position disclosed in Figures 1 and 3.

It will be readily understood that by a variation 35 on the tension of springs 40 and 59 in the manner previously described that the operating differential of the instrument may be widely varied and that either end of the operating differential may be shifted independently of the other. It 40 will also be readily understood that the mechanism may be advantageously utilized either as a high pressure cutout or as a low pressure cutout dependent only upon the positioning of mercury switch 97. For example, if the switch operates 45 as a high pressure cutout it will be so positioned that the electrodes (not shown) are in the left hand end of the switch as viewed in Figure 1, whereas, if it is desired to utilize the mechanism as a low pressure cutout the electrodes will be 50 positioned in the right hand end of the switch as seen in Figure 1.

It may be here pointed out that under exceptional circumstances such as a complete absence of pressure in housing 11, operating rod 12 may 55 drop to such an extent as to permit disalignment of member 15 with its associated levers 20 and 21. To preclude this happening a spring 110, see Figure 2, is positioned about the upper portion of operating rod 12 and seated on an annulus 111. Spring 110 thus serves to urge member 15 into 60 engagement with its associated levers 20 and 21 regardless of the position of operating rod 12.

From the foregoing it will now be seen that 65 there is herein provided an apparatus accomplishing all the objects of this invention and others including many advantages of great particular utility and importance.

As many embodiments may be made of this 70 invention and as many modifications may be made in the embodiment herein described and shown in the accompanying drawing, it is to be understood that all matter herein is to be interpreted as illustrative and not in a limiting 75 sense.

I claim as my invention:

1. In a device of the character described, in combination, a movable member, a lever freely pivoted thereon, a pair of levers movable by said first mentioned lever, a pair of springs each 5 biasing one of said pair of levers in a direction towards said first mentioned lever, means for varying the tension in each of said springs and mechanism operated by said pair of levers.

2. In a device of the character described, in 10 combination, a movable member, a transverse member pivoted thereto, a pair of levers, pivoted at the extremities of said transverse member, a pair of springs, each biasing one of said levers toward said extremities, means for varying the 15 tension in each of said springs and mechanism operated by said pair of levers.

3. In a device of the character described, in 20 combination, a member movable in response to variations in the value of a condition, a second member pivoted thereon, a pair of levers movable by opposite ends of said second member, resilient means biasing each of said levers towards said second member, means for varying the biasing 25 effect of said resilient means and mechanism operated by said levers.

4. In a device of the character described, in 30 combination, a movable member, a second member movable thereby, levers associated with opposite ends of said second member, means exerting a force on each of said levers, means to vary the force so exerted, and mechanism operable by said levers.

5. In a device of the character described, in 35 combination, a movable member, condition responsive means to move said member, a transversely disposed member pivoted substantially at its mid point on said movable member, levers pivotally mounted on each end of said transversely disposed member, resilient means urging 40 said levers towards said last mentioned member, means to vary the resiliency of said resilient means and condition control mechanism operated by said levers.

6. In a device of the character described, in 45 combination, a movable member, a rod exerting a force on said member at an intermediate point, levers abutting said member at each extremity, fulcrums for said levers, means exerting a force on each of said levers at their extremities opposite those abutting said member, mechanism operated by said levers, and means to vary the force exerted by said means.

7. In a device of the character described, in 55 combination, a movable member, a rod exerting a force on said member at an intermediate point, levers abutting said member at each extremity, fulcrums for said levers, means exerting a force on each of said levers at their extremities opposite those abutting said member, mechanism 60 operated by said levers, and means to vary the force exerted by said means on the ends of each of said levers independently.

8. In a device of the character described, in 65 combination, a movable member, a rod exerting a force on said member at an intermediate point, levers abutting said member at each extremity, fulcrums for said levers, means exerting a force on each of said levers at their extremities opposite those abutting said member, mechanism operated by said levers, means to vary the force exerted by said means on the ends of each of said levers independently, and visual means indicative 70 of the force exerted on each of said levers.

9. In a device of the character described, in combination, switch means, means to move said switch means, said last mentioned means comprising a pin and a pair of members in abutting relationship with opposite sides of said pin, one of which serves to move said pin in one direction and the other of which serves to move said pin in the other direction, means to move each of said members independently, and means precluding the movement of said member which moves said pin prior to the movement of the other of said members in a direction away from said pin.

10. In a device of the character described, in combination, a tiltable mercury switch, means to tilt said switch, said last mentioned means comprising a pin and a pair of members in abutting relationship in abutting opposite sides of said pin, one of which serves to move said pin and hence tilt said switch in one direction, and the other of which serves to move said pin and hence said switch in the other direction, means to move each of said members independently, and means precluding movement of said member which moves said pin prior to movement of the other of said members in a direction away from said pin.

11. In a device of the character described, in combination, a tiltable mercury switch, means to tilt said switch, said last mentioned means comprising a pin and a pair of members in abutting relationship with opposite sides of said pin, one of which serves to move said pin and hence said mercury switch in one direction and the other of which serves to move said pin and said switch in the other direction, condition responsive means to move each of said members independently in response to changes in the value of a condition, and means precluding movement of said member which moves said pin prior to movement of the other of said members in a direction away from said pin.

12. In a device of the character described, in combination, a movable member, condition responsive means to move said member, a transversely disposed member pivoted substantially at its mid point on said movable member, levers pivotally mounted on each end of said transversely disposed member, resilient means urging said levers towards said last mentioned member, means to vary the resiliency of said resilient means and a mercury switch tiltable in one direction by one of said levers and in the opposite direction by the other of said levers.

13. In a device of the character described, in combination, a movable member, a transverse member pivoted thereto, a pair of levers pivoted at the extremities of said transverse member, a pair of springs each comprising one of said levers towards said extremities, means for varying the tension in each of said springs, a mercury switch support, a mercury switch carried thereby, means to tilt said support, said means comprising a projection carried by each of said levers, the arrangement being such that one of said levers tilts said switch in said one direction and the other of said levers tilts said switch in the opposite direction, and condition control mechanism operated by said mercury switch.

14. In a device of the character described, in combination, a movable member, a transverse member pivoted thereto, a pair of levers pivoted at the extremities of said transverse member, a pair of springs each biasing one of said levers towards said extremities, means for varying the tension in each of said springs, visual indicating

means indicating the tension in each of said springs, a mercury switch support, a mercury switch carried thereby, means to tilt said support, said means comprising a projection carried by each of said levers, the arrangement being such that one of said levers tilts said switch in said one direction and the other of said levers tilts said switch in the opposite direction and condition control mechanism operated by said mercury switch.

15. In a device of the character described, in combination, a condition responsive device, a lever, a member operated by said condition responsive device engaging said lever at a point intermediate its ends, a first means exerting a force on said lever on one side of said point, a second means exerting a force on said lever on the other side of said point, and switch means operated by said lever.

16. In a device of the character described, in combination, a condition responsive device, a lever, means connecting said condition responsive device with a point on said lever intermediate its ends, a first spring tending to rotate said lever in one direction about said point, a second spring tending to rotate said lever in the other direction about said point, means for adjusting said springs, and a control device operated by said lever.

17. In a device of the character described, in combination, a condition responsive device, a lever, means connecting said condition responsive device with a point on said lever intermediate its ends, a first spring tending to rotate said lever in one direction about said point, a second spring tending to rotate said lever in the other direction about said point, said springs being connected to said lever at opposite sides of said point, means for independently adjusting said springs, and switch means operated by said lever.

18. In a device of the character described comprising in combination, a mercury switch, a pivotally mounted support therefor, a pin carried by said support, a first member engaging said pin to move it in one direction, a second member engaging said pin for moving it in the other direction, and condition responsive means for moving said first member at only one value of the condition and said second member at only another value of the condition.

19. In a device of the character described comprising in combination, a mercury switch, a pivotally mounted support therefor, a pin carried by said support, a first member engaging said pin to move it in one direction, a second member engaging said pin for moving it in the other direction, condition responsive means for moving said first member at only one value of the condition and said second member at only another value of the condition, and means for independently adjusting the values of the condition at which said condition responsive means moves said first and second members.

20. In a device of the character described comprising in combination, a switch casing, a mercury switch, a support therefor pivotally mounted within said casing, a pin carried by said support, a first member engaging said pin to move it in one direction, a second member engaging said pin to move it in the other direction, condition responsive means for moving said first member at one value of said condition and said second member at another value of said condition, means extending outside of said casing for independently adjusting the values of the condition at

which said condition means move said first and second members, and means outside of said casting for indicating said condition values at which said members are moved.

5 21. In a device of the character described, in combination, a condition responsive device, an operating member, means operatively connecting said condition responsive device to said operating member at an intermediate point, means exerting a force on said member at one side of said intermediate point, means exerting a force on said member at the other side of said intermediate point, said forces being exerted on said member in substantially the same direction, and switch 10 means actuated as a result of movement of said operating member.

22. In a device of the character described, in combination, a condition responsive device, an operating member, means operatively connecting 20 said condition responsive device to said operating member at an intermediate point, means exerting a force on said member at one side of said intermediate point, means exerting a force on said member at the other side of said intermediate 25 point, said forces being exerted on said member in substantially the same direction, switch means actuated as a result of movement of said operating member, and means for adjusting at least one of said forces.

30 23. In a device of the character described, in combination, a condition responsive device, a control member, means operatively connecting said condition responsive device and an intermediate point on said member, first and second stop means 35 cooperating with said member, means exerting a force on a first end of said member on one side of said intermediate point, and means exerting a force on a second end of said member on the other side of said intermediate point, said 40 forces being exerted on said member in substantially the same direction and so proportioned that as said condition responsive device moves in one direction it causes the first end of said member to move into cooperation with said first stop means 45 and then causes said second end of said member to move into cooperation with said second stop means and as said condition responsive device moves in the opposite direction it first causes said second end of said member to move out of 50 cooperation with said second stop means and then causes said first end of said member to move out of cooperation with said first stop means.

55 24. In a device of the character described, in combination, a condition responsive device, a control member, means operatively connecting said condition responsive device and an intermediate point on said member, first and second stop means 55 cooperating with said member, means exerting a force on a first end of said member on one side of said intermediate point, means exerting a force on a second end of said member on the other side of said intermediate point, said forces being exerted on said member in substantially the same direction and so proportioned that as said condition responsive device moves in one direction it

causes the first end of said member to move into cooperation with said first stop means and then causes said second end of said member to move into cooperation with said second stop means, and as said condition responsive device moves in the opposite direction it first causes said second end of said member to move out of cooperation with said second stop means and then causes said first end of said member to move out of cooperation with said first stop means, and means for adjusting at least one of said forces independently of the other.

5 25. In a device of the character described, in combination, a condition responsive device, a control member, means operatively connecting said 15 condition responsive device and an intermediate point on said member, first, second, third, and fourth stop means for said member, means exerting a force on a first end of said member on one side of said intermediate point, and means 20 exerting a force on a second end of said member on the other side of said intermediate point, said forces being exerted on said member in substantially the same direction and so proportioned that as said condition responsive device moves in one 25 direction it causes the first end of said member to move into cooperation with said first stop means and then causes said second end of said member to move into cooperation with said second stop means, and as said condition responsive device 30 moves in the opposite direction it first causes said second end of said member to move out of cooperation with said second stop means and into cooperation with said third stop means and then causes said first end of said member to move out of 35 cooperation with said first stop means and into cooperation with said fourth stop means.

26. In a device of the character described, in combination, a condition responsive device, a control member, means operatively connecting said 40 condition responsive device and an intermediate point on said member, first, second, third, and fourth stop means for said member, means exerting a force on a first end of said member on one side of said intermediate point, means exerting 45 a force on a second end of said member on the other side of said intermediate point, said forces being exerted on said member in substantially the same direction and so proportioned that as said condition responsive device moves in one direction it causes the first end of said member to move into cooperation with said first stop means and then causes said second end of said member to move into cooperation with said second stop means 50 and as said condition responsive device moves in the opposite direction it first causes said second end of said member to move out of cooperation with said second stop means and into cooperation with said third stop means and then causes said first end of said member to move out of 55 cooperation with said first stop means and into cooperation with said fourth stop means, and means for adjusting at least one of said forces independently of the other.

ALBERT E. BAAK.
